UNITED STATES PATENT OFFICE.

JOHN A. BURRISS, OF DES MOINES, IOWA.

TOY.

1,363,307.

Specification of Letters Patent. Patented Dec. 28, 1920.

Application filed January 21, 1918, Serial No. 212,983. Renewed April 30, 1920. Serial No. 378,014.

To all whom it may concern:

Be it known that I, JOHN A. BURRISS, citizen of the United States of America, and resident of Des Moines, Polk county, Iowa, have invented a new and useful Toy, of which the following is a specification.

The object of this invention is to provide an improved construction for a top and means for spinning the same.

10 A further object of this invention is to provide an improved construction for a holder for a top to initiate the spinning of said top.

My invention consists in the construction, 15 arrangement and combination of elements hereinafter set forth, pointed out in my claims and illustrated by the accompanying drawing, in which—

Figure 1 is a side elevation showing the 20 holder and top mounted therein. Fig. 2 is a plan of the same. Fig. 3 is a plan of a portion of the holder, showing a slightly modified construction.

Fig. 4 is an elevation of the top, showing 25 a construction modified somewhat from that shown in Figs. 1 and 2. Fig. 5 is a side elevation, opposite to Fig. 1, showing the holder modified particularly for use with the top shown in Fig. 4. Fig. 6 is an end 30 view of the same.

In the construction of the device as shown a holder is employed, comprising a handle portion 10 and a head portion 11 integral therewith and preferably somewhat enlarged in its vertical dimension relative to 35 said handle. The head 11 is formed with a vertical slot 12 opening to its outer end and a horizontal slot 13 opening to its outer end and crossing said vertical slot, both of 40 said slots being centrally located in said head, the slot 13 preferably being of greater length than the slot 12. For use in connection with the holder so formed a top is provided, having a body portion 14 suitably tapered to a spinning point, and an 45 upwardly extending stem or spindle 15 centrally of said body. The stem or spindle 15 of the top preferably is slightly longer than the vertical dimension of the head 11 50 of the holder, and said stem or spindle is adapted to be mounted therein as shown, through the vertical slot 12, with the upper end projecting above said head and the top body 14 depending below the holder. The 55 vertical slot 12 is formed with a curved bearing or seat 16 at its inner end corre-

sponding in curvature to the stem or spindle 15 and forming a seat therefor. The stem or spindle 15 also is formed with a reduced portion 17 intermediate of its ends 60 and adapted to have a cord such as 18 wound thereon in a common manner. The reduced portion 17, bearing the cord 18, is adapted to register in use with the horizontal slot 13, which provides space for said 65 cord and permits the free end thereof to project laterally from the holder as shown for manipulation to impart spinning motion to the top. The cord 18 preferably is so wound that the free end emerges at the 70 outer side of the spindle, or the side away from the bearing 16 of the slot 12, so that the tendency, in applying draft to said cord, is to hold the spindle or stem 15 in its bearing until the cord is removed.

In use the parts are assembled as shown, 75 the top being retained in the holder by contact of the point thereof with the floor or surface on which the top is to spin, or by contact of a finger of the operator, on the hand engaging the handle 10, with the upwardly projecting end of the stem 15 to hold said stem in the bearing 16. The operator then employs his other hand to apply draft to the cord 18 to the end of unwinding 80 said cord from the reduced portion 17 of the spindle, and imparting a rotary motion to the top. When the cord is released from the spindle the top is removed from the holder by either downward or outward 85 movement through the slot 12, and will spin for quite a long time.

In the modification shown in Fig. 3 one 90 of the upper arms of the head 11^a is cut away or shortened as at 19. This is on the rear side of the holder, or on the side away from which the stem 15 is turning in its 95 rotary motion, and it is the function of this construction to permit the finger of the operator to engage around the upper end 100 of the stem to hold it in place prior to spinning. This simply permits a little better engagement of the stem by the operator's finger than the other construction shown and previously described.

In Fig. 4 I have shown the top having a head or knob 20 on the upper end of the spindle, said head being adapted to rest above and upon the head 11 of the holder and prevent downward movement of the 110 top. In other words the top is suspended in the holder by engagement of the head

or knob 20 with the top of the holder. In this construction the top must necessarily be removed from the holder by outward movement through the slot 12.

5 For use with the type of top shown in Fig. 4 I have shown in Figs. 5 and 6 a special form of holder, which may be used or not as desired. In this construction the upper rear arm of the head 11^b is of less 10 elevation than the upper forward arm as formed by the intersecting slots 12, 13, such arm being indicated by the numeral 21. When the top is mounted in this form of holder the knob or head 20 rests on the head 15 11^b and contacts with the forward arm of said head, which is in the same plane as the head proper, but does not contact with the rear arm 21, which is in a lower plane. The rotary motion of the head 20, contacting 20 on one side only, and that on the side toward which it is moving, gives to said head a tendency to travel outwardly through the slot 12, after the cord 18 is released, to the end of removing the top from 25 the holder. It is to be understood, however, that either form of top shown may be employed with either form of holder, the special modifications being shown as illustrative of constructions and arrangements 30 which may be employed without departing from the spirit of my invention, and I do not desire to be understood as limiting myself to any particular form or construction of top or holder except as defined by the 35 appended claims.

By employing the holder here shown and described, a top may be imparted a spinning motion with ease and the top will spin much longer than if the spinning were initiated without mechanical adjuncts. A 40 heavier top, that will gain more momentum, can be spun in this manner than could be spun by the fingers alone.

I claim as my invention—

45 1. A device of the class described, comprising a holder formed with a vertical, end-opening slot at one end, and also formed with a horizontal, end-opening slot crossing said vertical slot, said horizontal slot being longer than said vertical slot, and a top 50 formed with an upwardly projecting stem adapted to be seated in said vertical slot, said stem being formed with a reduced portion registering with said horizontal slot, 55 and adapted to receive a cord.

2. A device of the class described, comprising a holder formed with a vertical slot at one end, and also formed with a horizontal slot crossing said vertical slot, said 60 horizontal slot being of greater length and also of greater breadth than said vertical slot, and a top formed with a stem adapted

to project upwardly through said vertical slot, said stem being formed with a reduced portion registering with said horizontal slot 65 and adapted to receive a cord, said cord adapted to pass laterally through said horizontal slot at right angles to the trend of said vertical slot.

3. A device of the class described, comprising a holder formed with a vertical slot at one end, and also formed with a horizontal slot crossing said vertical slot, and a top formed with a stem located above the body thereof and adapted to pass upwardly 75 through said vertical slot, said stem being adapted to receive a cord adapted to pass laterally through said horizontal slot, said holder being located wholly above the body 80 of the top.

4. A device of the class described, comprising a holder formed with a vertical slot at one end, and also formed with a horizontal slot crossing said vertical slot, and a top formed with an upwardly projecting 85 stem, the body of the top being adapted for mounting below said holder with the stem projecting through said vertical slot, said stem being adapted to receive a cord passing through said horizontal slot, said stem 90 being formed with an enlarged head adapted to rest on top of said holder.

5. A device of the class described, comprising a holder formed with a vertical slot at one end, and also formed with a horizontal slot crossing said vertical slot, and a top formed with an upwardly projecting stem, the body of the top being adapted for mounting wholly below said holder with the stem projecting upwardly through said 95 vertical slot, the upper rear arm of said holder formed by said intersecting slots being foreshortened for engagement of the operator's finger with the upper end of said stem.

6. A device of the class described, comprising a holder formed with a vertical slot at one end, and also formed with a horizontal slot crossing said vertical slot, and a top formed with an upwardly projecting 100 stem, the body of the top being adapted for mounting beneath said holder with the stem projecting upwardly through said vertical slot, said stem being formed at its upper end with an enlarged head adapted to contact with the top of the holder, the upper rear arm of the holder, formed by the intersecting slots, being of less elevation than the plane of the top of the holder, and not contacted by said head.

Signed by me at Des Moines, Iowa, this eighteenth day of January, 1917.

JOHN A. BURRISS.
